UNITED STATES PATENT OFFICE.

FRANK MOLESTA AND JACOB M. MOLESTA, OF PARIS TOWNSHIP, KENT COUNTY, AND DWIGHT S. COLE, OF GRAND RAPIDS, MICHIGAN; SAID COLE ASSIGNOR TO SAID FRANK MOLESTA AND SAID JACOB M. MOLESTA.

SPRAY-NOZZLE AND MOUNTING THEREFOR.

1,177,884.

Specification of Letters Patent. Patented Apr. 4, 1916.

Application filed October 1, 1915. Serial No. 54,699.

To all whom it may concern:

Be it known that we, FRANK MOLESTA, JACOB M. MOLESTA, and DWIGHT S. COLE, citizens of the United States, residing, respectively, in Paris township, in the county of Kent and State of Michigan, in Paris township, in the county of Kent and State of Michigan, and in the city of Grand Rapids, in the county of Kent and State of Michigan, have invented a new and useful Improvement in Spray-Nozzles and Mountings Therefor, set forth in this specification and illustrated by the accompanying drawing, forming a part hereof.

Our invention relates to an improved spray nozzle and mounting therefor and more particularly to that type of such devices as are employed in connection with revoluble lines of pipes forming part of a showering system for use in greenhouses, gardens, etc.

The objects of our invention are to provide a spray nozzle and mounting therefor which may be easily and securely applied to a line of pipe; renders the repeated removal and replacement of the nozzles for cleaning or change of size easy and practical; enables nozzles of the deflector type to be easily and accurately set with respect to the direction of their discharge; provides simple, durable and tight joints that are not liable to get out of order, and accomplishes these objects with parts that are simple and easily produced. These and other objects of our invention will more fully appear from the following description.

Our invention consists essentially of the various novel features of construction, combination and arrangement of parts herein after more fully described; and particularly pointed out in the appended claims, and the accompanying drawing illustrates several variations in the forms which the parts may have without departing from the essential common principles of the invention.

A spray nozzle and mounting constructed in accordance with our invention comprises in combination a pipe having a screw-threaded orifice in the wall thereof; a bushing having a screw-threaded portion adapted to screw into the said orifice in the pipe and make a tight joint therebetween; a head on said bushing whereby the bushing may be turned by a suitable tool to screw the

bushing into or remove it from the pipe; a 55 socket in the bore of said bushing, and a nozzle having a stem portion adapted to pass through the bore of said bushing and provided with suitable surfaces to engage the said socket and be secured therein by the 60 frictional contact of the engaging surfaces—the contact of said engaging surfaces forming a tight joint between the socket and stem of the nozzle.

An additional feature of our improved 65 spray nozzle and mounting consists in making the head portion of the nozzle larger in diameter than the stem which passes through the bushing and to have the bottom face of the bushing and to have the bottom face of the head portion somewhat spaced apart 70 from the top face of the bushing so that a suitable tool may be applied in the recess thus formed to lift and free the nozzle from tight engagement in the socket when it is desired to remove the nozzle from the bush- 75 ing.

Referring now to the drawing: Figure 1 is a side elevation of a piece of pipe having our improved bushing, and a nozzle therein, secured in the wall thereof; Fig. 2 is a transverse section on line A—B of Fig. 1; Fig. 3 is an exterior side view of the nozzle shown in section in Fig. 2; Fig. 4 is a central sectional elevation of a collar, similarly shown in the assembly in Fig. 2, which is employed 85 in this form of our improved mounting; Fig. 5 is a central sectional elevation of the bushing employed in this form of our improved mounting, showing the form of socket therein; Fig. 6 is a top view of 90 Fig. 7; Fig. 7 is a central sectional elevation of a bushing and nozzle therein of a second form of our improved mounting; Fig. 8 is an exterior side view of the nozzle shown in section in Fig. 7; Fig. 9 is a central sectional 95 elevation of the bushing employed in the second form of our improved mounting, showing the form of socket therein; Fig. 10 is a central sectional elevation of a bushing and nozzle therein of a third form of our 100 improved mounting; Fig. 11 is an exterior side view of the nozzle shown in section in Fig. 10; Fig. 12 is a central sectional elevation of the bushing employed in the third form of our improved mounting, showing 105 the form of socket therein; Fig. 13 is a central sectional elevation of a bushing and nozzle therein showing a fourth form of our

improved mounting; Fig. 14 is an exterior side view of the nozzle shown in section in Fig. 13; Fig. 15 is a central sectional elevation of the bushing employed in the fourth form of our improved mounting, showing the form of socket therein; Fig. 16 is an external side view of our improved bushing with like views of the projecting portions of a nozzle therein; Fig. 17 is a central sectional elevation, on the line C—D of Fig. 16, of a bushing and nozzle therein showing the fifth form of our improved mounting; Fig. 18 is a section on line E—F of Fig. 17; Fig. 19 is an exterior side view of the nozzle shown in section in Fig. 17, and Fig. 20 is a central sectional elevation of the bushing employed in the fifth form of our improved mounting, showing the raised margin at the top of the socket thereof.

20 Like numbers refer to the same parts throughout the several views.

Referring to the drawing it will be observed that the several figures show but one form for the exterior of the bushing, and 25 essentially equivalent devices for securing the nozzle in the bushing. The several figures also show variances in the shape of the deflector generally employed with this type of spray nozzle, which feature is illustrated 30 and described to assist in making clear how our improved mounting provides for the very important matter of being able to face all of the nozzles on a pipe in any desired direction and secure them equally tight regardless of the direction they face, which 35 conditions are not satisfied by the direct screwing of the stem of the nozzle into the orifice of the pipe as has been the common practice heretofore.

One form of our improved mounting is disclosed by Figs. 1, 2, 3, 4 and 5, in which 1 is a piece of pipe having a tapped orifice 2 in the wall thereof; 3 is a bushing tightly secured, in orifice 2 by a tapered screw 46 thread 4 thereon; 5 is an annular head, preferably knurled, on bushing 3 to which a tool 50 may be applied to turn the bushing in screwing it into or removing it from the pipe; 6 is the bore of the bushing 3 having an enlarged portion 7 at its upper end and an 55 annular shoulder 8 at the bottom of the enlarged portion 7; 9 is a ring, preferably of lead or other soft metal, adapted to fit into the portion 7 of the bore 6 and have its face 60 contact with shoulder 8; 11 is the spray nozzle adapted to be used in this form of our improved mounting; 12 is the stem of the nozzle which passes freely through the bore of the bushing and ring 9; 13 is the 65 main portion of the bore of the stem 12; 14 is the throat of the nozzle; 15 is the conical section of the bore of the nozzle connecting portions 13 and 14 thereof; 16 is the body portion of the nozzle; 17 is an 70 enlarged portion between stem 12 and body

16; 18 is the annular shoulder between portion 17 and body 16; 19 is the annular shoulder between portion 17 and stem 12, said shoulder being adapted to contact with the top face 20 of the ring 9; 21 is the deflector in body 16 of the nozzle, and 22 is the top surface of body 16.

In the second form of our improved mounting, shown by Figs. 7, 8 and 9, the bore of the bushing has a cylindrical part 75 23, and a conical part 24, forming a socket to receive the contact portion 25, in the form of the zone of a sphere, on the stem of the nozzle.

In the third form of our improved mounting, shown by Figs. 10, 11 and 12, the bore of the bushing is cylindrical its entire length and that portion 26 of the stem of the nozzle adjoining its head is made slightly conical for a short length, as shown by Fig. 11. 85

In the fourth form of our improved mounting, shown by Figs. 13, 14 and 15, the bore of the bushing is made slightly conical for a considerable portion of its length, forming a socket 27, and the stem of the nozzle has 90 a portion 28 made conical to accurately fit into the conical socket, as shown by Fig. 13.

In the fifth form of our improved mounting, shown by Figs. 17, 19 and 20, the bore 95 of the bushing is cylindrical its entire length and a raised annular edge 29 is provided at the top of the bore, as shown by Fig. 20, against which a shoulder 30 on the nozzle impinges, as shown in Fig. 17. 100

In showering systems of the revoluble pipe type as heretofore constructed the spray nozzles commonly employed have been of the single piece deflector type having threaded stems screwing directly into tapped orifices in the wall of the pipe. The stem of such a nozzle was generally about three-sixteenths of an inch in outside diameter and when the area of the hole in the stem was deducted from the cross-section the remaining metal was too weak to withstand the stress and frequently broke, leaving a portion in the orifice in the pipe, when being screwed into the pipe. Such breakage was greatly increased by the extra stress, beyond making a leak-tight screwed joint, necessarily applied to many of the nozzles to force them around to a position where their faces were in common alinement, which is a necessary condition of such a showering system. Moreover, it has been found necessary in practice to remove and replace nozzles in order to clear out obstructions from their passages, and in such cases many nozzles have heretofore been broken off because the threaded joint had set so firmly as to require a greater force to start it to unscrew than the stem would stand. 110

The losses and troubles due to breakage from the above-enumerated causes have been 115

so great as to render that type of mounting the nozzles very unsatisfactory. To overcome these defects we have studied out and invented an improved method of mounting 5 such nozzles, as shown and described herein, which is free from the defects mentioned and very perfectly meets all of the essentials for such service.

Our improved mounting provides a 10 simple bushing to be screwed tightly into and remain permanently in the orifice in the wall of the pipe; a nozzle having a threadless stem passing through the bore of the bushing, which provision enables the nozzles 15 to be set facing any desired direction; suitable contacting surfaces on the stem of the nozzle to engage suitable surfaces of the bushing to enable sufficient friction to be set up between the said contacting surfaces 20 as to hold the nozzle securely in place by friction alone against its expulsion by the pressure of the water in the pipe, and this friction grip provides for the repeated easy removal and perfect and easy replacement 25 of the nozzle in the socket of the bushing when conditions so require, thus perfectly satisfying that requirement of service.

The parts of our improved mounting are 30 shown full size, for the designated service, by the drawing and an inspection of the drawing will show that the parts are simple in form and capable of being easily and cheaply made.

In practice, the bushing of our improved 35 mounting is screwed into the tapped orifice in the wall of the pipe, until a leak-tight joint is made therebetween, then the nozzle is placed in position with its face in the desired direction and a light rap or 40 blow on top 22 of the nozzle drives the contacting surfaces together so tightly as to set up sufficient friction therebetween to clamp the stem of the nozzle securely and thus hold the nozzle in place against such 45 pressures as are ordinarily used in this service.

In the form of our improved mounting shown by Figs. 1, 2, 3, 4 and 5, the soft metal ring 9 is compressed between shoulders 8 and 19, when the force of the blow 50 on head 22 acts to drive the said shoulders together, and this swaging action causes the soft metal of the ring to flow laterally 55 and its side surfaces to thus make intimate contact with the respective surfaces to which they are opposed, thus sealing the stem of the nozzle in the bushing leak-tight and secure by the friction set up between the lateral contacting surfaces of the mounting. 60 The soft metal of ring 9 will readily hold to permit of withdrawing the stem of the nozzle repeatedly therethrough and as readily yield to swagings to repeatedly close the joint as securely as at first.

65 In all of the forms of mountings shown

by the drawing the stem 12 of the nozzle makes a close yet free fit in the lower part of the bore 6 of the bushing, which provision assists in making all forms of the mounting effective. 70

In the form of contacting surfaces shown in Figs. 7, 8 and 9 the zone-shaped surface 25 makes linear annular contact with the surface of the slightly conical socket 24 and a rap on the head or top 22 of the nozzle 75 forces the contacting surfaces together so intimately as to produce a leak-tight and sufficiently secure joint therebetween.

The form of contacting surfaces shown by Figs. 10, 11 and 12 produces annular 80 contact between the annular edge 31 and the slightly conical surface 26, and, as the parts of our improved mounting (except ring 9) are preferably made of a malleable composition of metals, as brass, the effect of a rap 85 on top 22 of the nozzle is to force the contacting surfaces 26 and 31 intimately together and thus make a leak-tight and secure friction joint therebetween.

The form of contacting surfaces shown 90 by Figs. 13, 14 and 15 is truly and slightly conical, and cone 28 accurately fits into conical socket 27, so that when forced together by a rap on top 22 of the nozzle the 95 conical surfaces come into such intimate contact as to form a leak-tight and adequately secure joint for the purpose.

In the form of mounting shown by Figs. 17, 19 and 20 an annular marginal collar 29 of the form shown is provided on the top 100 of the bushing and an annular shoulder 30 is provided on the nozzle to contact with the top edge of the said collar to the end that when these parts are forced together by a rap on top 22 the collar 29 will be swaged 105 and compressed tightly around the stem 12 so as to form a leak-tight joint therebetween to adequately secure the nozzle in the bushing.

While we have shown several of the forms 110 which the contacting surfaces in our improved mounting may be given we do not limit ourselves to the specific forms shown and described, but would include as within the scope of our invention all forms of frictional contacting surfaces which produce a leak-tight and sufficiently secure joint to serve the purpose, substantially as described. 115

What we claim as our invention is:—

1. In a spray nozzle and mounting therefor, the combination of a nozzle having a stem portion smaller in diameter than the head portion thereof; an axial bore through said stem; an orifice through said head to said bore in said stem; a screw-threaded 120 bushing adapted to be secured in an orifice in a wall of a chamber; a head on said bushing adapted to the application of a tool thereto to screw the bushing into or remove it from said orifice; an axial bore through 125

1 said bushing adapted to receive the stem of
2 said nozzle and by frictional engagement of
3 the contacting portions thereof make a se-
4 cure and tight joint between said nozzle and
5 said bushing—the proportions of the parts
6 being such that when said nozzle is firmly
7 secured in said bushing the top surface of
8 said bushing and the bottom surface of said
9 head portion of said nozzle will be spaced
10 apart to admit of the insertion of a tool
11 therebetween to facilitate the removal of
12 said nozzle from said bushing, substantially
13 as shown and described.
14 2. In a spray nozzle and mounting there-
15 for, the combination of a nozzle having a
16 head with a notch providing a deflecting
17 surface located in the side thereof; a stem
18 smaller in external diameter than said head—
19 that portion of said stem adjoining the said
20 head being somewhat larger in diameter
21 than the free end portion thereof; a hole
22 through said stem and the base portion
23 of said head into said notch; a screw-
24 threaded bushing adapted to be firmly se-
25 cured in an orifice in the wall of a chamber;
30 a head on said bushing adapted to the ap-
31 plication of a tool thereto to screw said
32 bushing into or remove it from said orifice;
33 a bore through said bushing adapted to
34 freely admit the free end portion of said
35 stem of said nozzle therethrough and to
36 make contact in its outward portion with
37 the attached and somewhat enlarged por-
38 tion of said stem, so as to make a secure and
39 tight joint to mount the stem of said nozzle
40 in said bushing by the frictional contact of
41 the engaging parts thereof—the proportions
42 of the parts being such that when said noz-
43 zle is firmly secured in said bushing the top
44 surface of said bushing and the bottom sur-
45 face of said head portion of said nozzle will
46 be spaced apart to admit of the insertion of
47 a tool therebetween to facilitate the removal
48 of said nozzle from said bushing, substantially
49 as shown and described.
50 3. In a spray nozzle and mounting there-
51 for, the combination of a nozzle having a
52 head with a notch providing a deflecting
53 surface located in the side thereof; a stem
54 smaller in external diameter than said head
55 portion and in axial alinement therewith—
56 said stem being conical and somewhat en-
57 larged in that portion adjoining the said
58 head; an axial bore through said stem and
59 the base portion of said head into said
60 notch; a screw-threaded bushing adapted to
61 be firmly secured in an orifice in the wall of
62 a chamber; a head on said bushing adapted
63 to the application of a tool thereto to screw
64 said bushing into or remove it from said
65 orifice; an axial bore through said bushing
66 adapted to freely admit the free end por-
67 tion of said stem of said nozzle there-
68 through and to make contact in its out-
69 ward portion with the conical portion of
70 said stem, so as to make a secure and tight
71 joint to mount the stem of the nozzle in the
72 bushing by the frictional contact of the en-
73 gaging parts—the proportions of the parts
74 being such that when said nozzle is firmly
75 secured in said bushing the top surface of
76 said bushing and the bottom surface of said
77 head of said nozzle will be spaced apart to
78 admit of the insertion of a tool therebetween
79 to facilitate the removal of said nozzle from
80 said bushing, substantially as shown and de-
81 scribed.
